UNITED STATES PATENT OFFICE.

LORY L. LITTLEFIELD, OF BELLEVUE, IOWA.

PROTECTOR FOR HARNESS-STRAPS.

1,112,708.

Specification of Letters Patent.

Patented Oct. 6, 1914.

Application filed June 16, 1914. Serial No. 845,457.

To all whom it may concern:

Be it known that I, LORY L. LITTLEFIELD, a citizen of the United States, residing at Bellevue, in the county of Jackson and State 5 of Iowa, have invented a new and useful Protector for Harness-Straps, of which the following is a specification.

The present invention appertains to a protector for harness straps and which is adapted particularly as a sheath or wear member 10 for a belly band to reduce the wear incident to the rubbing of the pole strap.

The present invention aims to provide a simple and inexpensive protector of unique 15 construction, which will be applicable to the belly band or other strap in a simple, but effective manner, to prevent the wear of the belly band or strap.

It is also the object of the present invention to provide a protector or sheath which 20 will be applicable to various sizes of belly bands or other straps, which will not require any special tools to apply the same, and which may be readily stamped or formed 25 from sheet metal.

With the foregoing and other objects in view which will appear as the description 30 proceeds, the invention resides in the combination and arrangement of parts and in the details of construction hereinafter described and claimed, it being understood that 35 changes in the precise embodiment of the invention herein disclosed can be made within the scope of what is claimed without departing from the spirit of the invention.

The invention has been illustrated in its preferred embodiment in the accompanying drawing, wherein:—

Figure 1 is a perspective view of the protector. Fig. 2 is a cross sectional view 40 thereof.

The improved protector or sheath is formed from a blank of sheet metal, of suitable dimensions. The protector embodies 45 an elongated plate or body 1 having its edge portions 2 and 3 curved back, whereby the protector will be of approximately elliptical cross section. The reflexed or inwardly turned edge portions 2 and 3 are spaced 50 apart, whereby the protector or sheath may be readily slipped transversely over the belly band or other strap.

As a means for connecting the edges of the plate or body 1, and for contracting the 55 protector or sheath, the edge portion 2 is provided with a longitudinal series of in-

tegral tabs 4 which are provided with longitudinal slots 5, and the other edge portion 3 is provided with a longitudinal series of flexible or bendable tongues 6, the free ends 60 of which are insertible through the slots 5 of the tabs 4. When the free ends of the tongues 6 are inserted through the slots 5 they are adapted to be bent back, as seen at 65 7 in Figs. 1 and 2, to thereby hold the edge portions 2 and 3 of the sheath or protector against separation. The tabs 4 and tongues 6 at the opposite sides are in transverse alignment, whereby they will coöperate 70 properly, it being preferable to provide a tab 4 and a tongue 6 at each end of the sheath or protector.

In order to hold the sheath or protector in place upon the belly band or strap, the edge portions 2 and 3 are provided intermediate the respective tabs 4 and tongues 6 with angular teeth or spurs 8 which project inwardly at points spaced slightly from the sides of the protector or sheath.

It will thus be observed that the protector 80 or sheath is formed from a single blank, and may be inexpensively and conveniently manufactured. The protector may be readily applied to a belly band or strap, when the tongues 6 are detached from the 85 tabs 4, inasmuch as the belly band or strap may be readily passed laterally through the opening between the edge portions 2 and 3 to be received by the protector or sheath. Then, the edge portions 2 and 3 are bent 90 toward each other, which may be done by means of any suitable implement which is handy, and as a result the teeth or spurs 8 will be caused to bite or engage into the belly band or strap, to hold the protector 95 against longitudinal movement along the belly band or strap and furthermore, the protector or sheath will be contracted snugly about the band or strap to tightly embrace the same. During the contraction of the 100 protector or sheath, the free ends of the tongues 6 are passed through the slots 5 of the tabs 4, and when the sheath is properly contracted, the free ends of the tongues 6 are bent back, as at 7, by means of a hammer 105 or other suitable implement, to thus hold the protector or sheath in contracted condition. The body or plate 1 will thus provide a suitable wearing surface, for the contact of the pole strap or other strap crossing the belly band or strap to which the 110 protector is applied. In this manner, the

wear of the belly band or strap to which the protector is applied is eliminated. The protector or sheath may be applied to old, as well as new harnesses and may be constructed of light or heavy stock, according to the various circumstances. When the protector or sheath is applied to the belly band or strap, the protector or sheath will not unduly encumber the same. It is also to be observed that no special tools are necessary for applying or removing the protector, other than a pair of pliers and a hammer, or their equivalents.

Having thus described the invention, what is claimed as new is:—

- 15 1. A protector for belly bands and the like, embodying a plate having its edge portions curved back, one edge portion having slots, and the other edge portion having flexible tongues insertible through the said slots and adapted to have their free ends bent back.
- 20 2. A protector for belly bands and the like, comprising a plate having its edge portions curved back, one edge portion having a longitudinal series of tabs, the tabs having slots, and the other edge portion having a longitudinal series of flexible tongues in-

sertible through the said slots and adapted to have their free ends bent back.

3 3. A protector for belly bands and the like, embodying a plate having its edge portions curved back, one edge portion having slots, and the other edge portion having flexible tongues insertible through the said 34 slots and adapted to have their free ends bent back, the said edge portions having inturned teeth.

4. A protector for belly bands and the like, comprising a plate having its edge portions curved back, one edge portion having a longitudinal series of tabs, the tabs having slots, and the other edge portion having a longitudinal series of flexible tongues insertible through the said slots and adapted 45 to have their free ends bent back, the said edge portions having inturned teeth between the respective tabs and tongues.

In testimony that I claim the foregoing as my own, I have hereto affixed my signature in the presence of two witnesses.

LORY L. LITTLEFIELD.
